United States Patent Office

Des. 208,584
Patented Sept. 12, 1967

208,584

PUNCHING MACHINE OR SIMILAR ARTICLE

Irwin Susskind, Brooklyn, N.Y., assignor, by mesne assignments, to Houdaille Industries, Inc., Buffalo, N.Y., a corporation of Michigan

Filed June 8, 1966, Ser. No. 2,612

Term of patent 14 years

(Cl. D55—1)

FIG. 2FIG. 3FIG. 4FIG. 5FIG. 1 is a front perspective view of a punching machine showing my design.

FIG. 2 is a side elevational view thereof showing the side opposite to that shown in FIG. 1.

FIG. 3 is a top view thereof.

FIG. 4 is a front elevational view thereof.

FIG. 5 is a rear elevational view thereof.

The dominant features of my design reside in the full lines.

I claim:

The ornamental design for a punching machine or similar article, substantially as shown and described.
